UNITED STATES PATENT OFFICE.

WILLIAM C. SCHMIDT, OF RICHMOND, VIRGINIA.

INDICATING-BOTTLE.

1,326,974.

Specification of Letters Patent.

Patented Jan. 6, 1920.

Original application filed February 24, 1909, Serial No. 479,737. Divided and this application filed May 8, 1917. Serial No. 167,266.

To all whom it may concern:

Be it known that I, WILLIAM C. SCHMIDT, a citizen of the United States, residing at Richmond, in the county of Henrico and 5 State of Virginia, have invented certain new and useful Improvements in Indicating-Bottles; and I do hereby declare the following to be a full, clear, and exact description of the invention, such as will enable others 10 skilled in the art to which it appertains to make and use the same.

My invention consists in the novel features hereinafter described, reference being had to the accompanying drawings which 15 show two embodiments of the invention, which I have selected for purposes of illustration, and the said invention is fully disclosed in the following description and claims.

20 Referring to the said drawings,

Figure 1 is a vertical sectional view of one form of my improved bottle and closure, with the stopper retracted.

Fig. 2 is a similar view of a modification, 25 with the stopper closed.

Fig. 3 is a top plan view of the neck partition disk.

Fig. 4 is a top plan view of a tubular member which is adapted to be placed in 30 the neck of the bottle.

Fig. 5 is a similar view of a modified form of neck partition disk taken on line $x-x$ of Fig. 2.

Fig. 6 is a side view of the bottle neck 35 after said bottle has been originally filled and closed.

Fig. 7 is a similar view showing the bottle open and that an attempt has been made to refill it.

40 My invention relates to non-refillable bottles and consists in certain novel and useful improvements in the same and is a division of my application, Serial No. 479,737 filed Feb. 24, 1909.

45 The object of my invention is to provide a closure for bottles intended to contain various kinds of liquids, so constructed as to permit the contents of a bottle to be freely poured therefrom but which will indicate 50 with certainty any attempt to insert liquid into the bottle after it has once been emptied or partially emptied of its original contents.

To this end I provide my improved bottle with an indicating device having a part 55 which is adapted to be totally or partially

destroyed, disintegrated or removed by chemical action, which is set up by liquid coming in contact with a part impregnated with chemicals, thereby carrying with it a 60 word or indication or symbol, showing the contents to be original and on dissolution, displaying a word or other indication showing the bottle to be refilled.

In the embodiment of my invention illustrated in Figs. 1, 3 and 4, A designates the neck portion of my improved bottle provided with my invention, and having internal screw threads a as shown. B is a tubular member forming part of the closure 70 for the bottle and is provided near its lower edge and on its periphery with a screw threaded annular portion b adapted to engage the screw threads a in the neck of the bottle.

75 F is a packing washer of cork or other suitable material seated in a recess in the neck of the bottle below the threads a , against which the lower end of the tubular member B is screwed, to prevent the contents of the bottle from passing the threads and entering a recess C' located between the tubular member B and the upper end of the neck of the bottle. At the top of the tubular member B is an annular disk or 80 flange C provided on its periphery with serrations c and connected to said member B by means of a screw threaded joint H. The periphery of this disk C is the same in circumference as the inner surface of the neck 85 of the bottle, so that it will fit the same snugly and only permit communication between the recess C' and the upper end of the bottle through the openings formed by the serrations c.

90 K is an inner cylinder located within and forming part of the member B, and being integral with the same through the medium of ribs d', the openings between the ribs forming channels e. The upper end of the cylinder K has a single screw thread c^2 to receive the shank c^3 of the stopper D and the lower end of said cylinder is closed by means of a stopper k to prevent the outflowing liquid from the bottle entering said cylinder.

100 The lower portion of the part B is provided with an annular partition I of some suitable transparent substance, such as glass, forming two chambers, one for each of the 110 two ribbons of the indicator G, hereinafter described. This partition I is in effect a

baffle and extends upwardly in plane with a circular line drawn through the disk C, a slight distance toward the center of the tubular member B from the inner edges of 5 the serrations c , so that liquid entering the recess C' through the openings formed by the serrations will drop first into the chamber formed between the partition I and the inner surface of the neck of the bottle.

10 The stopper D may be of any desired form, the one shown consisting of a main portion D' provided with the before mentioned threaded shank C³. The stopper is provided with cored washers which close 15 the mouth of the bottle and channels c when the stopper shank C³ is screwed into the opening c^2 . A ring d is placed upon the lower end of the shank C³ in order to prevent said shank from being withdrawn entirely from the cylinder K.

15 The indicator G, which is placed in the recess C', consists of a ribbon G' or strip of any suitable material, such as paper, fabric, tape, etc., with an indication of fraud thereon, such as the word "Refilled" 20 coated with a mixture of a non-transparent substance and chemicals, such as whiting mixed with a non-hygroscopic substance, as a carbonate and preferably bicarbonate of 25 soda, which conceals the fraud indication. 30 On this coating appears by printing, stamping or otherwise, any desired word or words, marks or symbols indicating originality of the contents, such for example as the word 35 "Original" which indications are visible through the bottle as shown in Fig. 6. This ribbon is placed in the chamber formed between the partition I and the inner surface of the neck of the bottle and another ribbon G² is placed in the chamber formed 40 between the partition I and the member B.

45 This second ribbon G² is preferably formed of absorbent material, which is impregnated with a non-hygroscopic solid acid, such for example as citric acid, which is easily soluble in liquid.

50 When an attempt is made to refill the bottle, the inflowing liquid will pass through the serrations c and drop into the chamber carrying the ribbon G' and the partition I will prevent said liquid from entering the chamber carrying the ribbon G² until enough liquid is forced into the outer chamber to overflow the partition, when chemical 55 and mechanical action ensues, which destroys the coating on which the indication of originality appears and the said coating is chemically removed carrying with it the indication of originality and displaying the 60 indication of fraud. The removal of the indication of originality and coating is mechanically accelerated by the action of the carbonic acid gas formed by the action of the chemicals used.

65 It is obvious that fraud indications on

the ribbon G', such as the word "Refilled" may be printed as heretofore described, and no further indication printed on the coating, the plain coating being the evidence of originality. In this case the attempt to refill the bottle would destroy the coating as heretofore described, and disclose the fraud indication, or the plain ribbon might be the indication of fraud, coated as described, with the symbol of originality thereon. In 70 this case, an attempt to refill the bottle would destroy the coating and the symbol of originality, leaving the plain ribbon to indicate fraud. Many variations of my improved indicating ribbon may occur in the 75 practical application of my invention.

80 The embodiment of my invention illustrated in Figs. 2 and 5, is identical with the structure heretofore described, except that the cylindrical portion K of the member B 85 is omitted, the threads being formed in the radial ribs L of the disk, Fig. 5, to engage the shank c^3 of the stopper D. In this view the indicating device is shown as a single structure of two ribbons placed back to 90 back, the outer ribbon bearing the fraud indication and coating of non-hygroscopic substance and the other ribbon being impregnated with acid. In these views I have also shown a conical valve X which is 95 loosely placed in the narrowed portion of the neck of the bottle, below the member B. This valve when the bottle is inverted will permit the ready outflow of the contents, but will act as an additional deterrent 100 to refilling the bottle, and in case an attempt is made to force liquid into the bottle the valve will close the bottle and positively cause the liquid to flood the recess in which the indicator is located.

105 The entire indicating device or double ribbon, in this instance, is placed in the inner chamber formed between the partition I and the outer surface of the member B, and it is obvious that the partition will protect 110 the ribbon from backward drippings, as said drippings would fall into the outer chamber between the partition and the inner surface of the neck of the bottle. If an attempt is made to refill the bottle, the 115 outer chamber would be quickly filled and overflow the partition I, and the liquid then entering the inner chamber will cause the chemical and mechanical action, heretofore described, to take place and display the indication of renewal.

120 It is obvious that other variations may be made in the details of the construction without departing from the spirit of my invention and I, therefore, do not limit myself 125 to the exact details herein described and shown.

What I claim and desire to secure by Letters Patent is:—

1. An indicating bottle of the kind de- 130

- scribed, having a member in the neck of the bottle provided with a recess forming with the neck of the bottle a chamber, an indicating device provided in said chamber 5 and visible from the exterior of the bottle and comprising layers of suitable material, one layer being provided with an indication and the other layer being impregnated with an acid, and a baffle located adjacent to said 10 chemical carrying materials and acting to prevent return drippings from outflowing liquid from reaching both chemical or materials carrying, the chemicals simultaneously.
- 15 2. An indicating bottle of the kind described, having in the neck thereof, an indicator visible from the exterior of the bottle, the said indicator comprising a substance carrying a non-hygrosopic carbonate, in 20 conjunction with an absorbent material carrying a non-hygrosopic acid, the acid being easily soluble in liquid, the two chemicals causing a chemical action to take place when inflowing liquid comes into contact 25 with them to disclose an indication of fraud.
3. An indicating bottle of the kind described, having in the neck thereof an indicator visible from the exterior of the bottle, the said indicator consisting of a 30 strip or ribbon coated with a mixture of non-transparent substance and a non-hygrosopic carbonate, and another strip of absorbent material carrying a non-hygrosopic solid acid.
- 35 4. An indicating bottle of the kind described having in the neck thereof a tubular member provided on its exterior with a recess, which forms with the neck of the bottle a chamber, an annular partition provided in 40 said chamber and dividing the lower portion thereof into a plurality of recesses, and an indicator provided in said chamber, visible from the exterior of the bottle and so located relative to said partition that one of 45 said recesses would have to be filled and overflowed with liquid before the indicating device would operate, said indicator comprising at least two chemicals and a fraud indicating character, and said indicating 50 character being invisible when the contents of the bottle is original, one of said chemicals being adapted to react chemically upon another when in solution caused by inflowing liquid, whereby said fraud indicating 55 character is exhibited to the vision.
5. An indicating bottle of the kind described, having in the neck thereof a tubular member provided on its exterior with a recess which forms with the neck of the bottle, 60 a chamber, an annular partition provided in said chamber and dividing the same into a plurality of annular recesses, and an indicator provided in said chamber and con-
- sisting of a plurality of strips, each of which carries a chemical substance, one of 65 said strips being also provided with a character representing a change in the original contents over which an opaque coating is placed, a symbol of originality provided on said coating, said indicator being visible 70 from the exterior of the bottle and being so located relative to said partition that one of said recesses would have to be entirely filled and overflowed with liquid before the chemical of one strip would react upon the chemical of the other strip to cause the destruction of the symbol of originality and coating and display the symbol of fraud.
6. An indicating bottle having in the neck thereof a tubular member provided on 80 its exterior with a recess forming with the neck of the bottle a chamber, a flange provided upon the upper end of said tubular member and having on its periphery a series of serrations through which said chamber 85 communicates with the upper end of the bottle neck, an annular partition provided in and dividing the chamber into a plurality of annular recesses, said partition being in effect a baffle and extending upwardly in 90 a plane with a circular line drawn through the disk C, a slight distance inwardly from the inner edges of said serrations, whereby liquid entering the chamber through the serrations will drop first into the chamber 95 formed between the partition and the neck of the bottle, and an indicator provided in said chamber, visible from the exterior of the bottle and so located relative to said partition that the outer recess must be entirely filled and overflowed with liquid before the indicating device operates.
7. An indicating bottle of the kind described, having in the neck thereof a tubular member provided on its exterior with a recess, which forms with the neck of the bottle a chamber, an annular partition provided upon the lower portion of said tubular member and extending vertically in said chamber and dividing the lower portion of the 105 chamber into a plurality of recesses, and an indicator consisting of a plurality of strips visible from the exterior of the bottle, one of said strips being provided in each of said annular recesses, the strip in one of said recesses carrying a chemical substance and an indicating character, and the strip in the other of said recesses carrying a different chemical substance, one of the recesses being adapted to be filled and overflowed with 110 liquid when an attempt is made to refill the bottle, whereby the two strips are brought into communication through the liquid and the identification of fraud exhibited.
- In testimony whereof I affix my signature. 115
WILLIAM C. SCHMIDT. 120
